UNITED STATES PATENT OFFICE.

MARTIN L. WILLIAMS, OF SOUTH BEND, INDIANA, ASSIGNOR, BY MESNE ASSIGNMENTS,
TO AMERICAN SLEEVE-VALVE MOTOR COMPANY, A CORPORATION OF DELAWARE.

ENGINE.

1,322,517.

Specification of Letters Patent.

Patented Nov. 25, 1919.

Original application filed April 18, 1913, Serial No. 761,930. Divided and this application filed December 5, 1914, Serial No. 875,625. Renewed October 17, 1919. Serial No. 331,495.

To all whom it may concern:

Be it known that I, MARTIN L. WILLIAMS, a citizen of the United States, residing in the city of South Bend, county of St. Joseph, and State of Indiana, have invented certain new and useful Improvements in Engines, of which the following is a specification.

This application is a divisional application of an original filed April 18th, 1913, Serial No. 761,930.

This invention relates to improvements in engines and refers more particularly to the actuating mechanism for operating the valve mechanism of a four cycle gas engine.

Among the salient objects of the invention are to provide a construction in which the valve ports of each cylinder are controlled by a single rotary valve all of which valves are actuated by a common driving member which is bodily adjustable; to provide a novel arrangement of valve actuating mechanism interposed between the crank shaft and valve sleeves which mechanism is enclosed in a suitable casing whereby it can be readily lubricated and kept clean; to provide a construction in which the gearing which is connected to the sleeves and the worm shaft mechanism which drives the gearing can be readily assembled and is so arranged as to avoid the necessity of too great nicety of adjustment and in general to provide improved mechanism of the character referred to.

35 In the drawings—

Figure 1 is a view partly in side elevation and partly in vertical section of my improved engine;

Fig. 2 is a transverse vertical sectional view;

Fig. 3 is an enlarged detail view of the worm shaft and associated parts;

Fig. 4 is an end view of the shaft shown in Fig. 3 with parts broken away to disclose certain details of construction;

Fig. 5 is a detail on an enlarged scale of the worm shaft adjusting mechanism.

Referring to the drawings—

1 designates as a whole the crank case, 2 the crank shaft and 3 the fly wheel. The crank is mounted in suitable bearings 4, 5, and 6. The lower end of the crank case serves as an oil pan 7 provided with oil troughs 8, 8. At the upper end the crank

casing is provided with a cylinder base 9 on which are supported the cylinders 10, 10. These cylinders are preferably constructed in pairs as shown, for example, in Fig. 1. These pairs of cylinders may each be removed independently of the other.

With each cylinder 10 is mounted the piston 11 connected by piston rod 13 to the crank 2 in any well known manner. Between each cylinder 10 and piston 11 is interposed a rotary valve sleeve 12 open at either end and extending the full length of the cylinder. To the lower end of each rotary valve sleeve 12 is secured a worm wheel 14, hereinafter more particularly described. In order to lubricate the various operating parts of the engine, in the upper part of the crank casing is formed a supplemental oil or lubricating chamber 46 which extends entirely around the base just below the lower ends of the four cylinders, as shown more clearly in Figs. 1 and 2. Oil is delivered to this chamber from the main supply chamber of oil reservoir 7 by means of a supply conduit 47 cast integrally with the upper and lower half of the crank case. Adjacent the rear pair of cylinders, this lubricating chamber 46 is provided with an enlarged extension 48 which is provided with a gear pump 49. The latter comprises a pair of gears 50 and 51 mounted on trunnions 52, and 53 journaled in suitable bearings. The trunnion of the shaft 53 of the gear is provided with an extension 53' carrying a spiral gear 54 which meshes with another spiral gear 55 mounted on a main worm shaft 56. The pump is provided with inlet ports 57 communicating with the conduit 47 and with an outlet 58 communicating with the supplemental lubricating chamber 46. The main object of the supplemental oil chamber 46 is that the worm shaft 56 which drives the rotary valve sleeves in the manner hereinafter described, shall be constantly incased in oil.

The outlet 58 is controlled by ported valve sleeves 58' and 59' leading to the oil chamber 46. The sleeve 58'' rotates and has a port 60' adapted to register with the port 59'. This latter sleeve 58'' is rotatably journaled in the stationary sleeve and is provided with an operating shaft 61' manually controlled by lever arm 62' leading to any convenient place. To prevent leakage a

washer 63' is interposed between a flange 64' and the threaded nut 65'. By adjusting the rotary sleeve the supply of oil from the pump can be readily controlled.

5 Describing now the manner of rotating the rotary valve sleeves, the worm shaft 56, heretofore referred to is mounted on suitable bearings 86, 87 and 88. The rear end of the shaft 56 is mounted in a thrust bearing 10 89 of well known construction. At its front end the worm shaft is provided with a pair of interlocking gears 90 and 91, the former receiving the link belt 84 for driving the fan and water pump. The latter gear 91 is connected directly to the crank shaft by a link belt 92, and gear 93, the latter being mounted on the front end of the crank shaft.

15 Means are also provided for bodily adjusting the worm shaft in its casing. Accordingly, in the front end of the worm shaft is rigidly mounted a male gear 94 intermeshing with female gear 95, the latter being bodily adjustable on the male gear and carrying the gears 90 and 91. The 20 gears 94 and 95 are locked in adjusted position by means of lock nut 96 and cotter key 97. On the worm shaft 56 are mounted four worm gears 98, 98. Each worm gear is provided at both ends with a conical counterbored portion 99 adapted to receive the conical ends 100 of lock nuts 101. These lock nuts are internally threaded as shown at 102 to engage threaded portions 103 on the worm shaft. By the arrangement just described the worms can be adjusted endwise 25 on the worm shaft, if necessary, and then positively locked in such adjusted position.

30 The flange 45 on the lower end of each sleeve is provided with three circumferentially spaced notched portions 104 adapted to register with the locking dogs 105 carried by a worm wheel 106. The worm 107 of each worm wheel 106 intermeshes with the corresponding worm wheels 98 and is thus 35 driven by the rotation of the worm shaft. Preferably, the lower ends of each worm wheel 106 are provided with a plurality of oil ducts 108. By reference to Fig. 2 it will be seen that these worm wheels are all 40 closed in the supplemental oil chamber. In 45

asmuch as the various ports in the rotary valve sleeve are all spaced equi-distant apart, and the locking recess 104 and locking dogs 105 are similarly spaced, the sleeve must of necessity be fitted in proper position.

55

I claim as my invention:

1. In a gas engine, the combination with a plurality of cylinders each having a piston and a ported rotary valve sleeve, of a crank casing and crank shaft therein, a worm shaft, gearing connecting said worm shaft to said sleeves, means for bodily adjusting said worm shaft, means for adjusting said gearing, and connections between said crank shaft and said worm shaft.

60

2. In a gas engine, the combination with a plurality of cylinders each having a piston and a ported rotary valve sleeve, of a crank casing and crank shaft therein, a second shaft, gearing connecting said second shaft to said sleeves, means for bodily adjusting said second shaft, means for adjusting said gearing, and connections between said crank shaft and said second shaft.

70

3. In a gas engine, the combination with a plurality of cylinders, each having a piston and a ported rotary valve sleeve, of a crank casing and crank shaft therein, a worm shaft, a worm gear thereon for each sleeve, means for adjusting each gear and said shaft, means for locking said gear in adjusted position, a worm wheel on the lower end of each sleeve meshing with the corresponding worm gear and connections between the worm shaft and the crank shaft.

75

4. In a gas engine, the combination with a plurality of cylinders each having a piston and a ported rotary valve sleeve, of a crank casing and a crank shaft therein, a driving shaft, means for bodily adjusting said latter shaft, driving members, means for adjusting said driving members relative to said driving shaft and connections between each driving member and a corresponding sleeve.
